COIN SLIDE

**Vesta K. Davis and Emma T. Davidson,
Winona, Minn.**

Application October 28, 1946, Serial No. 706,256

10 Claims. (Cl. 194—97)

1

This invention relates to improvements in vending machines and more particularly has to do with improved means for operating a device for clearing the selector mechanism of a slug or bent or sticky coins held therein.

-Coin selector mechanism commonly employed includes a magnet for sorting out slugs of substantial iron or steel. In the use of such mechanism, it often happens that slugs are held by the magnet. Bent or sticky coins also often become lodged in the selector mechanism. Provision has heretofore been made for clearing the selector mechanism of slugs or coins held therein, a push rod operating clearer device being provided for this purpose, the push rod being conveniently located at the front of the vending machine for operation by the customer. However, due to oversight on the part of the customer or lack of familiarity with the mechanism, the push rod is seldom operated by the customer and consequently the selector mechanism often becomes clogged, requiring frequent servicing by a repairman, it being necessary to take the coin chute apart.

The primary object of the present invention is to provide improved clearer device operating means of a simple, efficient, reliable nature, which will operate the clearer device to clear the selector mechanism every time a coin is delivered thereto and before another coin can be inserted in the machine, jamming of the selector mechanism being thus prevented.

Another object of the invention is to provide improved clearer device operating means of the character referred to of simple, practical construction that can be readily applied to well known types of coin selector mechanism.

The invention, with other objects and advantages thereof, and the particular construction, combinations and arrangements of parts comprising the same, will be understood from the hereinafter contained detailed description when considered in connection with the accompanying drawings, forming part hereof and illustrating one embodiment of the invention.

In the drawings:

Fig. 1 is a side elevation of coin selector mechanism equipped with clearer device operating means constructed in accordance with the present invention, the reciprocating coin receiver being shown in its outermost coin receiving position;

Fig. 2 is a side elevation taken from the side opposite that shown in Fig. 1;

Fig. 3 is a rear end elevation;

Fig. 4 is a front elevation;

2

Fig. 5 is a side elevation with parts shown in section:

Fig. 6 is a top plan view, the reciprocating coin receiver slide being shown in its outermost coin receiving position;

Fig. 7 is a vertical longitudinal section, the reciprocating coin receiver slide being shown at the end of its forward stroke;

Fig. 8 is a transverse vertical section taken on the line 8—8 of Fig. 1.

While a preferred embodiment of the invention is illustrated in the drawings, it will of course be understood that minor changes and modifications may be made in the particular construction shown, and the invention may be embodied in other forms as will appear to those skilled in the art and falling within the scope of the appended claims without departing from the spirit of the invention.

In the drawings, the invention is shown applied to coin selector mechanism of well known construction and the selector mechanism will therefore be referred to only in a general way. The selector mechanism is shown mounted upon a plate 1 suitably secured within the upper part of the vending machine casing 2. Hingedly connected to plate 1 is a plate 4, said plate being normally held in a closed retracted position, as shown in Fig. 1 of the drawings, by a coiled spring 5. The plate 4, when in closed retracted position, is spaced from the plate 1 and is so formed as to provide therewith a vertically extending chute section 4', and near its lower edge at the inner side thereof said plate is provided with an elongated track 6. Secured to the plate 1 is a plate 6' having a lower portion 6² spaced from the plate 1 a sufficient distance to provide a passageway for a normal coin so that it can pass laterally from the lower part of the vertically extending chute section 4' along the track 6. This track is inclined downwardly from its forward end to its rear end and serves as a track to receive incoming coins from the chute section 4' and to direct the same toward a chute (not shown) for receiving a

40 coin, which when of proper denomination and genuine, will at the proper point in its travel through the mechanism be in a position to operate the vending machine. In the present instance, the vending machine is designed to be operated by a nickel. Secured to plate 6 is a magnet 7 for sorting out slugs of substantial iron or steel. The selector mechanism also includes latch members 8 and 9. The latch member 8 is 50 pivotally mounted at 10 on the plate 1 to swing vertically parallel with said plate and has a finger

portion 8a extending transversely of the chute section 4', said latch member being weighted to normally assume the position shown in Fig. 2 of the drawings in the path of coins passing through said chute section. If the coin is a proper coin, it will by its weight force said latch member out of its path and pass to the track 6 whereas if it is a slug of less weight than a nickel it will be stopped by said latch. The other latch member 9 is pivoted at 11 to the plate 1 to swing vertically transversely of the chute section 4'. It has a transversely extending finger portion 9a, said latch member being normally held by a spring 45 in the position shown in Fig. 1 of the drawings with its finger portion 9a extending across the chute section 4'. The latch member 8 is provided with a forwardly extending portion at its lower end which engages the lower portion of the latch member 9 and moves the same outwardly to withdraw its finger piece 9a from across the chute section 4' when the latch member 8 is moved rearwardly out of operative position.

A blade 12 is pivoted to the inner face of the plate 1 at 13 for movement vertically between said plate and the hinged plate 4 to clear the selector mechanism of a slug or coin held between said plates. A coil spring 14 fastened to the blade 12 at one end and at its other end to the plate 1 acts to yieldingly hold the blade in its uppermost retracted position as shown in Fig. 1, the blade engaging a suitable stop on the plate when the same is in this position. Pivotally mounted on plate 1 at 15 above the blade 12 is a lever 16 for actuating the clearer blade 12, the lever being yieldingly held by a spring 17 in an elevated position with its free end portion engaging a stop portion on the plate 1 as shown in Fig. 2 of the drawings. The lever 16 has a transversely extending portion 16a to engage the upper edge of the clearer blade 12. Said lever also has a cam portion 16b to engage a roller 4a on the hinged plate 4, and a cam portion 16c to engage the upper end portion of the latch 8. When the lever 16 is depressed, the cam portion 16b and the cam portion 16c first engage the roller 4a and the upper portion of the latch 8 respectively to swing the hinged plate 4 outwardly and shift the latch 8. Upon a continued movement of said lever, the portion 16a on the lever engages the clearer blade 12, said blade being forced downwardly and caused to sweep through the space between the plates 1 and 6', thereby dislodging any coin that may be held therein, the dislodged coin being ejected from the machine through a discharge chute 18.

Referring now to a detailed description of the particular embodiment of the present invention illustrated in the drawings, the construction shown includes an elongated supporting member or frame having spaced parallel side wall portions 19, said supporting member being securely mounted to extend longitudinally through an opening 2a in the front wall of the casing 2 of the vending machine within the same a slight distance above the top of the selector mechanism, said supporting frame being fastened by bolts 20 or the like to the front wall 2 of the casing, the bolts 20 engaging apertured attaching lugs 47 on the supporting member or frame. The side wall portions 19 of the supporting member have downwardly depending lugs 21 at their inner ends that fit against a laterally extending plate portion 22 on the marginal portion of the plate 1. On the supporting frame 75 44 secured at one end to the coin receiver 26

or member between the side wall portions 19 thereof is a chute section 23, the lower end of which extends adjacent the upper end of the chute section 4' of the selector mechanism in register therewith. Forwardly of the chute section 23, the supporting member has integral solid portions 24 and 26, the portion 24 projecting forwardly of the front wall of the vending machine casing 2 as shown in Figs. 5 and 7 of the drawings. Extending upwardly from the supporting member at opposite sides of the forward part thereof within the opening 2a are tubular guide portions 29, and 30 is a tubular guide on the rear portion of the frame 19. Supported in said guides for reciprocatory longitudinal movement is a coin receiver 26, the same being in the form of a bar provided with a coin slot 27 extending vertically through the same and having a handle portion 28 at its forward end. The upper faces of the solid portions 24 and 46 of the supporting member, as shown in Figs. 5 and 7 of the drawings, extend level with each other and with the top edges of the chute section 23, said portions 24 and 46 constituting supporting and guiding means for a coin in the slot of the coin receiver bar 26. On the coin receiver bar 26 are laterally projecting stop portions 31 adapted to cooperate with the guide 29 to limit the outward movement of the coin receiver bar. Extending upwardly from the top of the portion 24 at its forward end is a lug 32, the receiver bar 26 being provided with a longitudinally extending slot 33 to accommodate said lug. Interposed between the lower portion of the handle portion 28 of the coin receiver 26 and the lug 32 is a coiled expansion spring 34, said spring acting to yieldingly maintain the coin receiver 26 in its outward coin receiving position as shown in Fig. 1 of the drawings. From the position shown in Fig. 1, the coin receiver is adapted to be forced inwardly against the tension of the coiled spring 34 to bring its coin slot 27 into register with the chute section 23 to deliver a coin to the chute section 4' of the selector mechanism, the coiled spring 34 acting to return the coin receiver to its outer position.

Supported for rotation in suitable bearings on the elongated supporting member or frame 19 at the rear thereof and rearwardly of the actuator lever 16 of the selector mechanism is a transversely extending shaft 37. One end of the shaft extends beyond one side wall portion 19 of the supporting frame 19 and has fixedly mounted thereon a star or cam wheel 38 provided with a plurality of cam portions 39 equally spaced about its periphery. The star or cam wheel 38, as shown in Fig. 6 of the drawings, is disposed in longitudinal alignment with the actuator lever 16 of the selector mechanism, the cam portions 39 on the star or cam wheel 38 being adapted to successively engage the free end portion of the actuator lever 16 and depress the same to actuate the clearer blade 12 upon a step by step rotation of the star or cam wheel 38. Fixedly mounted on the shaft 37 below the coin receiver 26 is a ratchet wheel 40, and 41 is a pawl on the coin receiver to cooperate with said ratchet wheel. One end of the pawl 41 is positioned in a slot 42 in the coin receiver 26 and pivotally connected with the coin receiver by a transverse pivot pin 43. The teeth 40a of the ratchet wheel 40 are hook shaped with curved outer faces 40b, and the pawl 41 has a hook shaped lower end portion 41a. A spring 75 44 secured at one end to the coin receiver 26

and having its other end engaging the pawl 41, serves to yieldingly maintain the pawl in the position shown in Fig. 1 of the drawings against a stop 44a on the coin receiver to engage a tooth of the ratchet wheel. The ratchet wheel has the same number of teeth as the number of cam portions 39 on the star or cam wheel 38 and the relative arrangement of the same is such that when the coin receiver 26 is forced outwardly by the spring 34 after an inward stroke of the same to deliver a coin to the chute 23, the pawl 41 will engage one of the teeth 40a of the ratchet wheel 40, and the ratchet wheel will be turned one tooth, the shaft 37 being turned to effect a partial revolution of the star or cam wheel 38 sufficient so that one of its cam portions 39 will engage and depress the lever 49 to actuate the clearer blade 42. Upon an inward stroke of the coin receiver 26, the outer curved face of the lower end 41a of the pawl 41 will ride over the outer curved face 40b of the adjacent tooth of the ratchet wheel, the pawl after it is carried out of engagement with the ratchet wheel being swung downwardly and forwardly back to normal position by the spring 34.

By the special construction and arrangement of parts herein before set forth, clearer device operating means of a simple, efficient nature is provided that insures the operation of the clearer device every time a coin is delivered to the selector mechanism and before another coin can be inserted in the vending machine so that jamming of the mechanism is positively prevented. The mechanism is simple and of compact construction that can be readily applied to standard types of selector mechanism.

What we claim is:

1. In a vending machine, the combination with a chute section, coin selector mechanism associated with said chute section adapted to allow proper coins to pass through the chute section and to arrest slugs therein, a movable blade member for clearing said chute section of a slug held therein, and spring means acting to normally maintain said blade member in inoperative position, of a reciprocating coin receiver having a coin slot and adapted to be manually operated inwardly to deliver a coin to said chute section, spring means acting to return the coin receiver to normal coin receiving position, and means controlled by said coin receiver acting automatically to actuate said blade member to clear said chute section in the return outward movement of the coin receiver to normal coin receiving position after an inward stroke of the same.

2. In a vending machine, the combination with a chute section, coin selector mechanism associated with said chute section adapted to allow proper coins to pass through the chute section and to arrest slugs therein, a movable blade member for clearing said chute section of a slug held therein, and spring means acting to normally maintain said blade member in inoperative position, of a reciprocating coin receiver having a coin receiving slot and adapted to be manually operated inwardly to deliver a coin to said chute section, and spring means acting to return the coin receiver to normal coin receiving position, said coin receiver being operatively connected with said blade member to actuate the same to clear said chute section when forced outwardly by the spring to normal position after an inward stroke of the same.

3. In a vending machine, the combination with

a chute section, coin selector mechanism associated with said chute section adapted to allow proper coins to pass through the chute section and to arrest slugs therein, and a blade member for clearing said chute section of a slug held therein, said blade member being pivotally supported at one end for vertical swinging movement, of a reciprocating coin receiver having a coin slot and adapted to be manually operated inwardly to deliver a coin to said chute section, and spring means acting to return the coin receiver to normal coin receiving position after an inward stroke of the same, said coin receiver being operatively connected with said blade member to actuate the same to clear said chute section in the return outward movement of the coin receiver to normal coin receiving position after an inward stroke of the same.

4. In a vending machine, the combination with a chute section, coin selector mechanism associated with said chute section adapted to allow proper coins to pass through the chute section and to arrest slugs therein, a vertically movable blade member for clearing said chute section of a slug held therein, and spring means acting to normally maintain said blade member in inoperative position, of a coin receiver supported for reciprocatory horizontal sliding movement above the chute section, said coin receiver having a coin slot therein and adapted to be manually operated inwardly to deliver a coin to said chute section, and spring means acting to return the coin receiver to normal position, said coin receiver being operatively connected with said blade member to actuate the same to clear the chute section in the return movement of the coin receiver to normal coin receiving position after an inward stroke of the same.

5. In a vending machine, the combination with a chute section, coin selector mechanism associated with said chute section adapted to allow proper coins to pass through the chute section and to arrest slugs therein, a vertically movable blade member for clearing said chute section of a slug held therein, and spring means acting to normally maintain said blade member in inoperative position of a coin receiver supported for reciprocatory horizontal sliding movement above the chute section, said coin receiver having a coin slot therein and adapted to be manually operated inwardly to deliver a coin to said chute section, a coiled expansion spring interposed between a part on said coin receiver and a stationary part, said spring acting to yieldingly maintain the coin receiver in an outward position to receive a coin, said coin receiver being operatively connected with said blade member to actuate the same to clear the chute section in the return movement of the coin receiver to coin receiving position after an inward stroke of the same.

6. In a vending machine, the combination with a chute section, coin selector mechanism associated with said chute section adapted to allow proper coins to pass through the chute section and to arrest slugs therein, a device for clearing the chute section of a slug held therein, a bar supported at one end for pivotal movement vertically, said bar being operatively connected with the slug clearing device to actuate the same, and a spring acting to yieldingly maintain said bar in substantially a horizontal position, of means for depressing said bar to actuate the slug clearer device including a reciprocating coin receiver slide having a coin slot therein and

adapted to be manually operated inwardly to deliver a coin to said chute section, a spring for returning the coin receiver slide to normal position, a rotary shaft extending transversely of said bar, a cam wheel on the shaft having a plurality of cam portions equally spaced about its periphery and adapted to engage a part on said bar and depress the same upon a partial revolution of the cam wheel, a ratchet wheel on said shaft, and a pawl on the coin receiver slide to engage and rotate the ratchet wheel one tooth to effect a partial revolution of said cam wheel to depress said bar in the return outward movement of the coin receiver to normal position.

7. In a vending machine, the combination with a chute section, coin selector mechanism associated with said chute section adapted to allow proper coins to pass through the chute section and to arrest slugs therein, a device for clearing the chute section of a slug held therein, a bar supported at one end for pivotal movement vertically, operatively connected with the slug clearer device to actuate the same, and a spring acting to yieldingly maintain said bar in substantially a horizontal position, of means for depressing said bar to actuate the slug clearer device including a reciprocating coin receiver slide having a coin slot therein and adapted to be manually operated inwardly to deliver a coin to said chute section, a spring for returning the coin receiver slide to normal position, a rotary shaft extending transversely of said bar near the free end thereof, a cam wheel on the shaft having a plurality of cam portions equally spaced about its periphery and adapted to engage a part on said bar and depress the same upon a partial revolution of the cam wheel, a ratchet wheel on said shaft, and a pawl yieldingly supported on the coin receiver slide to engage and rotate the ratchet wheel one tooth to effect a partial revolution of the cam wheel to depress said bar in the return outward movement of the coin slide to normal position.

8. In a coin selector mechanism for vending machines, the combination with a chute section, means associated with said chute section adapted to allow proper coins to pass through the chute section and to arrest slugs therein, a device for clearing the chute section of a slug held therein, a bar supported at one end for pivotal movement vertically, operatively connected with the slug clearer device to actuate the same, of means for depressing said bar to actuate the slug clearer device including a coin receiver supported for reciprocatory horizontal sliding movement above

the chute section, said coin receiver having a coin slot therein and adapted to be manually operated inwardly to deliver a coin to said chute section, a spring for returning the coin receiver to coin receiving position, a rotary shaft extending transversely of said bar, a cam wheel on the shaft having a plurality of cam portions about its periphery adapted to engage a part on said bar and depress the same upon a partial revolution of the cam wheel, a ratchet wheel on said shaft, and a pawl on the coin receiver slide to engage and rotate the ratchet wheel one tooth to effect a partial revolution of the cam wheel to depress said bar in the return outward movement of the coin receiver to normal position, said pawl being pivotally connected at one end to the coin receiver and extending downwardly therefrom, a stop on the coin receiver to limit the pivotal movement of the pawl forwardly and a spring on the coin receiver engaging the pawl and acting to yieldingly hold it against the stop in a position to engage the ratchet wheel.

9. In a vending machine, the combination with a chute section, coin selector mechanism associated with said chute section adapted to allow proper coins to pass through the chute section and to arrest slugs therein, a movable member for clearing said chute section of a slug held therein, of a reciprocating coin receiver having a coin slot and adapted to be manually operated inwardly to deliver a coin to said chute section, and means controlled by said coin receiver acting automatically to actuate said movable chute clearing member to clear said chute section in the return movement of the coin receiver to normal coin receiving position after an inward stroke of the same.

10. In a vending machine, the combination with a chute section, coin selector mechanism associated with said chute section adapted to allow proper coins to pass through the chute section and to arrest slugs therein, means for clearing said chute section of a slug held therein, of a reciprocating coin receiver having a coin receiving slot and adapted to be manually operated inwardly to deliver a coin to said chute section, and means controlled by said coin receiver acting automatically to actuate said first mentioned chute clearing means to clear said chute section upon the return movement of the coin receiver to normal coin receiving position after an inward stroke of the same.
